UNITED STATES PATENT OFFICE.

CHAUNCEY B. FORWARD, OF URBANA, OHIO.

APPARATUS FOR CONTINUOUSLY DISTILLING CRUDE OIL AND OTHER SUBSTANCES.

1,088,693.

Specification of Letters Patent.

Patented Mar. 3, 1914.

Application filed June 7, 1913. Serial No. 772,270.

To all whom it may concern:

Be it known that I, CHAUNCEY B. FORWARD, citizen of the United States, residing at Urbana, in the county of Champaign and State of Ohio, have invented certain new and useful Improvements in Apparatus for Continuously Distilling Crude Oil and other Substances, of which the following is a specification.

10 My invention relates to an apparatus for continuously fractionalizing crude oil and other substances, and the invention consists in the means substantially as hereinafter shown and described and more particularly 15 pointed out in the claims.

The primary object of the invention is to promote more or less instantaneous vaporization of the crude oil and a continuous fractional condensation thereof so as to separate the liquids of different gravities from each other, at the same time securing the asphalt base (which is the base of all mineral oils). By the term asphalt base I mean a substance similar to the natural product 25 but which would require a further treatment to make it substantially identical with the natural asphalt. This asphalt base can be secured in a liquid state, (corresponding with maltha), a semi-hard, or a hard state 30 from the first condenser. For instance, if I wish to obtain a liquid asphalt base among other divisions of the original oil running at the same time, my first condenser would be larger than if I were seeking 35 to obtain a hard asphalt base. In other words, if I wanted a hard asphalt base my first condenser would be small. In producing a semi-hard asphalt base the size of the first condenser would be between the small 40 and larger condenser according to the degree of hardness I wished to obtain. The asphalt base so obtained does not have the necessary adhesive and cohesive qualities to make it commercially valuable without further treatment as described in my other application of even date herewith, Serial No. 772,270, but by atomizing the crude oil and subjecting it to a forced travel through the retort while exposing it to suitable high 45 temperatures I can reduce the oil to its asphalt base in a continuous manner and trap off the base while simultaneously separating the other component parts of the crude oil in a more rapid and economical 50 manner than has been practicable heretofore, particularly with the use of only a

single retort. In so doing I obtain pure distillates without a repetition of heating operations at different temperatures in order to remove the various grades of oil or distillates, or in other words without following the common practice which consists in subjecting the oil to a specified temperature in a still until all the oil volatilizable at that temperature is removed, and then increasing 60 the temperature of the remaining product in the still to a given or certain higher degree of temperature, and continuing it at that higher temperature until all the volatilizable oil at the increased temperature 65 is removed, and then again increasing the temperature and so on until only coke is left as a residue.

In brief, my invention is particularly designed to treat crude oil or the residuum 75 thereof to obtain the asphalt base (the base of all mineral oils) at the outset and pure gasolene at the finish with all the intermediate distillates such as heavy and light paraffins (or heavy and light lubricating oils 80 if the so-called asphalt base oils are being treated), kerosene, naphtha, etc. To accomplish this result successfully with all the different kinds of crude oil obtainable, requires a convertible apparatus, and one of 85 my objects is to provide a series of sectional condensing chambers having sectional condensing elements and pipe connections adapting interchange and different working relations between the parts so that the 90 product from the retort may be variably acted upon at different points in the line of its discharge to produce a variety of similar distillates from different grades of oil or to produce different varieties of distillates from the same grade of oil. 95

In the accompanying drawings Figure 1 shows a sectional view of a retort and a side view of six sectional condenser columns connected in series therewith, and also an oil 100 pump and air compressor. Fig. 2 is a plan view in section of the retort shown in Fig. 1. Fig. 3 is a sectional view vertically of one of my improved condensers embodying two sections and the removable elements there- 105 in. Figs. 4 and 5 are perspective views of the two disk-shaped elements forming the interior parts of each condenser. Figs. 6 and 7 are side views corresponding to Fig. 1 except for a different working relation be- 110 tween the condenser parts.

The retort A as such is shown in Figs. 1

and 2 as consisting of a series of pipes 2 arranged in parallel relation on a successively downward plane within a protecting jacket 3 which may be filled with super-heated steam if desired. Pipes 2 may be 22 feet in length, more or less, as the work may require and the ends thereof are united by suitable connections 4 located on the outside of the retort. Removable plugs 5 in connections 4 permit cleaning of the pipes from the outside of the retort. The connections 4 unite pipes 2 so as to make a continuous coil, each pipe 2 being fully exposed to the super-heated steam in the jacket 3 or other transmitting agent. The jacket and not the pipes are directly exposed to the flames from the gas burner B and heating of the oil is therefore uniform throughout the full length of the pipes 2. In lieu of a single large jacket for all the pipes I may use a small jacket for each length of pipe. The crude oil is pumped into the intake end 6 of the first pipe 2 of the coil by a pipe 7 leading from oil pump 8, and this intake end is also connected to an air or steam supply tank or compressor 9 by a pipe 10. The flow of liquid is continuous and under a sustained pressure of about forty pounds, and the air or steam from pipe 10 is also continuously supplied at about the same pressure. A suitable nozzle 11 is used at the mouth or intake 6 to thoroughly atomize the oil as it is forced into pipe 2. A temperature of approximately six hundred and fifty degrees, Fahrenheit, is constantly maintained in the pipe 2 as shown by a thermometer or pyrometer 12 at the front end of the retort. This temperature I have found to be entirely satisfactory for reducing the atomized oil to a gaseous or vaporized state without undue coking. However, the asphalt which practically forms the base of all crude oils, is not vaporized under this temperature but is in such a liquid condition as to be as limpid as heavy paraffin oil at about a temperature of 175 degrees Fahrenheit, so that the pressure together with the downward inclination of the pipes in the retort as shown in Fig. 1, keeps it flowing. The object is to keep the oil in movement to prevent coking of the asphalt base while under such temperature as may be required to vaporize the lighter constituents of the oil, and the atomizing of the crude oil under pressure and its forced passage through pipes 2 permits the volatilization of the various grades of oils contained in the crude oil at one and the same time, thus avoiding a repetition of separate vaporizing operations at different temperatures as heretofore commonly practised. The temperature as given is not to be construed as the only temperature which can be used, as different kinds of oils require somewhat different temperatures according to their quality; but in every instance only a

single retort and a constant heat is employed.

The outlet end of pipe 2 connects with the base member 15 of the first column of one or more condenser units 16, a series of such columns D to I being arranged at equal distances apart and each column consisting of one or more of the units 16 with a sectional pipe connection 17 extending from the top member 18 of each column to the base member 15 of the next or succeeding column, as D to E, etc. Each unit comprises a metal pipe threaded at its ends to screw-engage the flanges 19 and 20 of the base and top members 15 and 18, respectively, or to screw engage the connecting band or ring 21 which unites two or more such units to provide a condenser of extended length and increased condensing surface and which surface may be more or less effectively utilized by superposing a greater or less number of spreader elements 22 and 23 within the units from the base 15 upward. The said units or sections 16 are closed circumferentially and open circumferentially internally between the upper and lower edges thereof to permit a free upward flow of the uncondensed oils in the condenser. Thus referring to Figs. 3, 4 and 5, the spreader elements comprise disk-shaped plates 22 and 23, alternately placed in superposed relation, element 22 having lips or projections 24 struck up radially of the body thereof and bent at right angles on both sides to provide supports therefor and for the other element 23 which is merely provided with a central opening 25. The displacement of the lips 24 in the element 22 leaves radial openings in the body thereof as seen in Fig. 5, and therefore when the two different elements are superposed the vapors which pass upward have an indirect travel through each column of unit or units.

In Fig. 3, the spreader elements are shown as completely filling the two units from top to bottom, but only the lower unit may be filled or the number of elements may be varied to meet any given need in any single column. The condensation from each column of units is discharged through a trap 26 before being permitted to pass into a suitable vessel 27, and at the start of operation the outlet side of the trap is closed by a valve 28 until sufficient liquid is trapped to seal each take-off pipe and prevent the loss of vapors at this point.

All of the units 15 are of like length and diameter and the pipe connections 17 between the separate column of condenser units have short sections of pipe 29 of the same length as the units which are connected by union nuts 30. These connections permit a continuous travel of the vapors from one column of units to the next until the last column I is reached, where a like pipe con-

nection 17 leads to a worm condenser J of usual construction, which condenser J is only necessary when an oil containing the gasolene is being handled. The number of condensers may be greater or less according to the size of the retort, the grade of oil to be treated or the character of the separations desired.

Now, referring to condenser column D (the first in the series), when the hot vapors reach this point only the heaviest portions which condense at a high temperature are precipitated and deposited in the first vessel d together with the asphalt base which has not been vaporized in the retort. This product in vessel d is the asphalt base and my aim is not to vaporize this part of the oil during its forced passage through the retort but only to subject it to such a temperature as will not cause coking. Obviously any temperature sufficient to vaporize the heaviest grades of oil contained in any or all of the crude oils will vaporize all the other lighter component parts and the base being drawn off without having been subjected to a temperature sufficiently high to have caused its coking, a great economy is effected. The vapors arising from condenser column D pass into the bottom of condenser column E and a so-called heavy paraffin oil is removed or separated at this point and discharged into the second vessel e. Such heavy paraffin oil is that constituent part which, when still incorporated with the asphalt base is often referred to as the residuum of crude oil as commonly refined. Condenser column F of three units (Fig. 1) in turn separates the light paraffin, and condenser column G of six units removes a so-called intermediate oil, whereas condenser columns H and I remove kerosene and naphtha respectively. Condenser J may be used to reduce the final vapors to gasolene.

Now a practical apparatus to fractionally separate various grades of oils in a continuous manner as described involves, first, the continuous feed of oil in a stream to the retort, second, atomization of the oil in the retort; third, the use of compressed air or steam to promote atomization and forced continuous movement of the oil through the retort; fourth, the exposure of atomized oil to a constant heat sufficient to volatilize substantially every constituent part of the oil except the base; fifth, the carrying forward of the vapors through separate condenser columns under more or less sustained pressure to produce continuous fractional condensation, and sixth, the use of convertible and interchangeable units for the different columns whereby continuous fractional separation may be effected in a varying degree at different points in the line of discharge and oils of different grades may be

separated as desired with the least trouble and expense.

To explain further, it is a well known fact that the various crude mineral oils from the different oil fields contain different grades and quality as well as quantity of the various oils from that of light in gravity to the heavy in gravity, therefore it is obvious that the arrangement of the units in the various condensing columns would depend entirely on the character of crude oil being treated and the character and gravity of the intermediate grades desired to be removed therefrom.

By way of illustration and referring to Fig. 6, let it be assumed that a high grade of kerosene is desired from a particular grade of oil, I would re-arrange the units into different working relations from that shown in Fig. 1 by removing four units from column H and transferring two of them to column G and the other two to column I, thereby making the condensing chamber for the kerosene smaller and the other condensing chambers for the intermediate oil and naphtha much larger. This arrangement of units will give a high grade of kerosene at vessel h as the lighter gravity which is usually classed with a lower fire-test kerosene passes on to column I and the heavier portion of the kerosene which retards the feed in the wick of a lamp remains behind and is condensed in column G. Fractional condensation is continuous but the result is different due to the rearrangement of units in the line of discharge and in respect to the traps and receiving vessels. This is further indicated in Fig. 7 where column F has been reduced to a single unit, column E to three units, and column G to seven units, thereby precipitating the heavier portions of the light paraffin oils in with the heavier paraffin of column E and passing the lighter portions of the paraffin usually taken at column F into column G, the product at column F being an intermediate or high grade paraffin or lubricating oil.

Now it is obvious that a single apparatus comprising the retort and the separate traps and columns of interchangeable units connected in series in the innumerable combinations made possible by my construction will afford a very economical means for fractionalizing the oils from various localities. In other words, Pennsylvania, Ohio, Colorado, Texas and California oils can all be handled with equal facility and success with my apparatus, and any one skilled in the art may vary the separations of the component parts of the oil from any given field according to the demands of the market. With some oils, one or more of the condenser columns may be cut out of the series entirely or one or more added thereto, or any one of the col-

umns may be subdivided into a series of smaller columns by using the units thereof to that end and employing a trap for each column.

5. An essential feature of this invention is the constant open communication between all the units in each column regardless of the number used and also regardless of the number of spreader elements used, and moreover, 10 the line of travel of the vapors through the retort and all the condensers combined is free and open regardless of any interchange or different combination of units in the respective columns.

15. What I claim is:

1. An apparatus for the continuous fractional separation of hydro-carbon oils comprising a multiple series of condensers having upper and lower end sections provided 20 with inlet and outlet openings respectively and intermediate interchangeable body sections circumferentially open internally from the upper edge to the lower edge and having solid closed sides, means separably uniting 25 said sections and adapting different collocations thereof to be made in the respective condensers and thereby increasing and decreasing the length of condensers relatively to one another according to the fractional 30 divisions of the oil desired from each, and pipes connecting the top section of one condenser with the bottom section of the next

succeeding condenser, in combination with means in advance of the series of condensers to vaporize the oil and force the vapors into 35 and through all the condensers in the series successively.

2. An apparatus for treating crude petroleum oils from different oil fields, the same comprising a plurality of condensers having 40 sectional bodies open internally about the wall thereof from bottom to top and a pipe having the same length of sections as said body sections connecting the top of one condenser with the bottom of the next succeeding 45 condenser and having bottom outlets for the distillates, the bodies of the said condensers consisting each of sections of the same size and interchangeable between condensers and said sections closed about their 50 sides and separably connected, thus adapting each condenser to be changed in size by adding to or taking from another condenser a portion or all of the units thereof according to the size and number of condensers wanted, 55 whereby any desired fractional separation of the oils can be secured and any crude hydro-carbon oil treated by said apparatus.

In testimony whereof I affix my signature in presence of two witnesses.
